(57) **CLAIM**

The ornamental design for a bicycle bar end, as shown and described.

DESCRIPTION

FIG. 1 is a front perspective view of a bicycle bar end of the present design, an opening for receiving a bicycle handlebar and a slot for assisting in attaching the bar end to the handlebar being shown in broken lines for illustrative purposes only and forming no part of the claimed design; FIG. 2 is a left side elevation view of FIG. 1 on a reduced scale; FIG. 3 is a bottom plan view of FIG. 2; FIG. 4 is a front elevation view of FIG. 2; FIG. 5 is a right side elevation view of FIG. 2; FIG. 6 is a top plan view of FIG. 2; and, FIG. 7 is a rear elevation view of FIG. 2. The broken lines shown herein are for illustrative purposes only and form no part of the claimed design.
